(57) **CLAIM**

The ornamental design for a uniform current distribution electrode for noninvasive brain stimulation, as shown and described.

DESCRIPTION

FIG. 1 is a top view of a uniform current distribution electrode for noninvasive brain stimulation showing our new design;

FIG. 2 is a cross-sectional view thereof taken along the line 2-2 in FIG. 1;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is an isometric view thereof.
